UNITED STATES PATENT OFFICE

2,482,874

LIPSTICK APPLICATOR

Helen Roland, Ringoes, N. J.

Application January 28, 1948; Serial No. 4,795

6 Claims. (Cl. 206—56)

1

This invention comprises novel and useful improvements in a lipstick applicator and more specifically pertains to a device for applying a cosmetic pencil or stick to the skin.

The principal object of this invention is to provide a cosmetic stick applicator wherein a stick of soft, moldable cosmetic material may be fed from the device as required, and wherein a reinforcing element is embedded in said stick to lend rigidity to the same, and which reinforcing element may be selectively and independently advanced or retracted as use of the device dictates.

An important feature of the invention resides in the provision of a novel construction of cosmetic stick applicator wherein independent means are provided for advancing and feeding a cosmetic stick from the device, and for advancing or retracting a reinforcing element embedded in said cosmetic stick; wherein the casing of the device is shaped to provide a guide at the dispensing opening of the casing for improving the feeding and use of the stick; and wherein a compact, simple but dependable mechanism is provided for positively advancing and retracting the reinforcing element as desired.

These, together with various ancillary objects and features of the invention which will later become apparent as the following description proceeds, are attained by this invention, a preferred embodiment of which has been illustrated by way of example only in the accompanying drawings, wherein:

Figure 1 is a longitudinal sectional view through a preferred embodiment of the invention; showing a cover positioned upon the device;

Figure 2 is a view similar to Figure 1 but showing the device with the cover removed and the applicator ready for use;

Figure 3 is an elevational view of the cosmetic stick holding unit of the invention;

Figure 4 is an elevational view of the reinforcement element operating means; and

Figure 5 is a vertical transverse sectional detail view taken substantially upon the plane of the section line 5—5 of Figure 1.

Referring now more particularly to Figures 1 and 2 of the accompanying drawings, wherein like numerals designate similar parts throughout the various views, the device is shown as consisting of a tubular casing 10 of any desired material, which is open at both of its ends and within which is screw-threadedly received the open end of a sleeve 12 which may likewise be of any desired material. Preferably, cooperating screw-threads 14 are provided between the telescoping

2

portions of the casing 10 and sleeve 12, as indicated at 14, whereby the sleeve may be adjusted within the casing for a purpose to be later set forth.

The other end of the casing 10 is preferably of reduced diameter as indicated at 16, and has an internal bore which is of reduced diameter compared to the bore of the casing 10, to constitute a guide for the end of the cosmetic pencil 18 which is slidably received within the casing 10. This pencil may conveniently comprise a lipstick, an eyebrow pencil but is not limited to these uses, since the principles of the invention are such that any cosmetic preparation of soft and moldable material may readily be dispensed and applied thereby.

As indicated also in Figure 3, the other end of the cosmetic stick 18 is securely retained in any desired manner within the open end of a thimble 20 of any suitable material, which thimble is provided with a reduced neck portion or extension 22 which is frictionally engaged or retained in any other manner preferably in a non-rotatable manner, in the open end of the sleeve 12.

Extending from the thimble 20, and within the neck portion 22, and disposed axially of the device, is a cylindrical extension 24 provided with a longitudinal slot 26.

This extension is received within the hollow interior of the sleeve 12, and extends throughout substantially the entire length thereof. At its outer end, the sleeve 12 is provided with a flange or enlarged portion 28, constituting a finger-grip means for rotating the sleeve within the casing, and also constituting a fastening and sealing means which is engageable with the interior wall of a tubular cover 30 which is closed at its other end. This cover may thus be frictionally applied to the device, for shielding the exposed end of the stick 18, and the member 28 thus serves both to retain the device in the cover by reason of the aforementioned frictional engagement and also serves to effect a seal to prevent the entry of dirt or other deleterious matter into the interior of the cover.

A knob or finger-grip member 32 provided with a depending skirt extension 34 is seated upon the outer end of the sleeve 12, with the skirt extension frictionally and rotatably received within the open outer end of the bore of the sleeve 12. Rigidly attached to the knob 32 and disposed axially thereof and extending through the skirt portion 34, is a spiral cam or spiral screw member 36, adapted to surround the cylindrical extension

24 within the sleeve 12 and likewise extending throughout substantially the entire length of the sleeve.

Since the cosmetic stick 18 is of soft, moldable material, it is subject to easy distortion particularly as regards its portion extended beyond the confines of the casing 10. Accordingly, a reinforcing element 38 in the form of a rod, wire or the like is embedded in the stick 18 and has its other end slidably received in the extension 24, with a laterally disposed finger portion 40 extending through the guide slot 26 for sliding and guided engagement therein. Thus, as the rod 38 is reciprocating, the finger 40 sliding in the slot 26 prevents rotation of the rod. This finger is engaged in the cam or screw track of the spiral member 36, whereby upon rotation of this member by the knob 32, the finger 40 will be moved longitudinally of the spiral member 36, and thereby advanced or retracted from its embedded position in the stick 18.

The operation of the device is as follows:

By rotating the sleeve 12 by manipulation of the member 28, the thimble and stick carried thereby may be selectively advanced or retracted from the guided end 26 of the casing, to expose the desired quantity of stick for convenient use of the same. As the stick is worn down, it becomes necessary to retract the reinforcing element 38, in order to prevent detrimental exposure of the end of this element from the end of the stick. Accordingly, the knob 32 may be rotated, thereby rotating the spiral member 36, and causing the above mentioned longitudinal movement of the finger 40 and of the reinforcing rod 38.

From the foregoing, the manner of constructing, and operating the device and the advantages arising therefrom will be readily understood and further explanation is believed to be unnecessary. However, since numerous changes and modifications will readily occur to those skilled in the art after a consideration of the foregoing specification and annexed drawings, it is not intended to limit the invention to the exact construction shown and described, but all suitable modifications and equivalents may be resorted to falling within the scope of the appended claims.

Having described the invention, what is claimed as new is:

1. A cosmetic applicator including a casing, a cosmetic stick slidably secured in said casing, means for adjustably moving said stick, a reinforcement extending axially into said stick, and further means for selectively and adjustably advancing and retracting said reinforcement independently of movement of said first means, said first means comprising a sleeve screw-threaded into one end of said casing, a thimble carrying

said stick, said thimble being slidable in said casing, a neck on said thimble seated in said sleeve, said further means including a spiral track, a finger on said reinforcement slidable in said track and means for preventing rotation of said finger.

2. The combination of claim 1, wherein said last means includes a cylindrical body carried by said thimble, a longitudinal guide slot in said body, said reinforcement being longitudinally slidable in said body and said finger extending through said slot.

3. A cosmetic applicator including a casing, a cosmetic stick slidably secured in said casing, means for adjustably moving said stick, a reinforcement extending axially into said stick, and further means for selectively and adjustably advancing and retracting said reinforcement independently of movement of said first means, said further means including a spiral track, a finger on said reinforcement slidable in said track and means for preventing rotation of said finger.

4. The combination of claim 3, wherein said last means includes a cylindrical body carried by said thimble, a longitudinal guide slot in said body, said reinforcement being longitudinally slidable in said body and said finger extending through said slot.

5. A cosmetic applicator comprising a casing, a sleeve screw-threaded into one end of said casing, a thimble slidable in said casing and carrying a cosmetic stick, said thimble having a neck received in said sleeve, a cylindrical extension on said thimble extending into said sleeve, a rotatable knob mounted on said sleeve, a spiral cam on said knob surrounding said extension and positioned within said sleeve, a reinforcement slidable in said extension and extending into said stick, a guide slot in said extension, and a finger on said reinforcement extending through said slot and engaging said cam.

6. The combination of claim 5, wherein the other end of said casing is of reduced internal diameter and comprises a guide for the end of said stick.

HELEN ROLAND.
